UNITED STATES PATENT OFFICE.

CHARLES P. WINEMAN, OF DETROIT, MICHIGAN, ASSIGNOR TO DETROIT TWIST DRILL COMPANY, OF DETROIT, MICHIGAN, A CORPORATION OF MICHIGAN.

MACHINE FOR STRAIGHTENING DRILLS OR THE LIKE.

Application filed July 3, 1919; Serial No. 308,500.

To all whom it may concern:

Be it known that E. CHARLES P. WINEMAN, a citizen of the United States of America, residing at Detroit, in the county 5 of Wayne and State of Michigan, have invented certain new and useful Improvements in Machines for Straightening Drills or the like, of which the following is a specification, reference being had therein to 10 the accompanying drawings.

The invention relates to machines for straightening cylindrical articles and particularly to machines designed for straightening drills or the like. One object of the invention is to provide a construction in which 15 the drill or the like is straightened between a pair of rollers. Another object is the provision of means for automatically moving one of the rollers toward and away 20 from the other roller to permit of the insertion or removal of the drill or the like between the rollers. A further object is to provide a common means for rotating the 25 rollers in the same angular direction; and also to provide an adjustable construction 30 for the purpose of operating upon different sized drills or the like. Other objects of the invention reside in the novel arrangements and combinations of parts as more fully hereinafter set forth.

In the drawings:

Figure 1 is a perspective view of the construction embodying my invention;

Fig. 2 is a vertical cross section thereof;

Fig. 3 is a front elevation of a portion of the rollers with a drill therebetween;

Fig. 4 is a vertical cross section through a portion of the machine on the axis of the 40 lower roller.

1 and 2 are respectively upper and lower rollers mounted in a suitable frame 3. 4 and 5 are gears upon opposite ends of the respective rollers 1 and 2 and preferably 45 outside the end standards 6 of the frame. 7 are pinions mounted upon opposite ends of the shaft 8 and meshing with the gears 4 and 5, the shaft 8 being driven by means of the belt wheels 9 upon its outer ends. 50 The driving arrangement is such that the rollers 1 and 2 are rotated in the opposite direction and at the same angular speed.

10 is a table pivotally mounted at the front side of the frame 3 and movable toward and away from the space between the 55

rollers 1 and 2 for the purpose of inserting the drill 11 or the like. As shown, this table is non-rotatably mounted upon shaft 12, which latter is rotatably mounted upon the frame 3. 13 are rock arms non-rotatably secured to the shaft 12 and extending laterally outward from the frame, these rock arms being pivotally secured to the rods 14 which extend downward adjacent to the bottom of the frame 3 and carry a suitable foot-operating member 15. 16 are links pivotally connected to the frame 3 and to the lower ends of the rods 14 to limit the inward movement of the lower ends of the rods 14. The arrangement of parts is 60 such that the inner end of the table 10 normally extends into the space between the rollers 1 and 2 and is adapted to move the drill or the like 11 into operative relation with the rollers. By moving the foot-operating member 15 downward the table can be rocked outwardly. This table is 65 preferably provided with the projection 17 upon its upper surface for holding the drill or the like thereon after disengagement 70 from between the rollers.

18 is an abutment or stop mounted upon the standards 6 and extending into the space between the rollers 1 and 2 a distance such that the axis of the drill or the like 11 when 75 inserted between the rollers can be in substantially the plane of the axes of the rollers. This stop or abutment prevents the drill or the like from being forced through the space between the rollers by the table 10. 80

To avoid the necessity of stopping the machine to remove the straightened drill or the like from between the rollers, the lower roller 2 is mounted to slide vertically up and down in the standards 6. For this purpose 85 it is mounted at its opposite ends in bearing blocks 19 beneath which extends suitable levers or rock arms 20 which are pivoted at one end 21 upon the standards 6. The free ends of these rock arms 22 have projections 100 23 extending into the paths of the cams 24. The latter are driven in time relation to the rollers 1 and 2 but at slower speed, and as shown are mounted upon the shaft 25 at the rear of the standards 1. Non-rotatably 105 mounted upon this shaft are the gears 26 which are driven from the lower roller 2 by means of the pinions 27 mounted upon the lower roller and the intermediate gears 28 rotatably mounted upon the standards 6. 110

The arrangement of parts is such that after the drill or the like 11 has been operated upon by the rollers for a predetermined length of time the low portion 29 of each cam 24 comes into registration with the projection 23 upon each rock arm or lever 20 and allows the latter to swing downwardly, which permits the bearings 19 carrying the lower roller 2 to move downward 10 by gravity. This automatically releases the pressure on the drill or the like and allows the latter to slide from between the rollers 1 and 2 and upon the table 10, when the latter has been lowered. The depths of the 15 teeth of the pinions 27 and gears 28 are sufficient to permit of this movement of the roller.

For the purpose of adjusting the machine to provide for different sizes of drills or the 20 like the following construction is provided: The upper roller 1 is mounted at its opposite ends in bearing blocks 30 which are vertically adjustably secured in the standards 6 as by means of the rods 31 secured to the bearing 25 blocks and threadedly engaging the standards. For the purpose of simultaneously adjusting these rods they are provided at their upper ends with suitable gears 32 which are adapted to be rotated from the shaft 33 extending 30 between the standards 1. The shaft 33 is rotated from the hand wheel 34 which is mounted upon the cross bar 35 extending between the standard 6.

For maintaining the pinions 7 in driving 35 relation to the pinions 4 and 5 upon the rollers the arms 36 and 37 are provided extending respectively from the upper bearing blocks 30 and the lower bearing blocks 19 to the bearings 38 carrying the shaft 8. By this arrangement when either of the rollers are vertically moved the arms connected to the bearing blocks of the roller moved will move the bearings 38 to maintain the pinions 7 in driving 40 relation with the gears of the rollers.

45 To maintain the belts 38 driving the belt wheels 9 sufficiently tight, the idler pulleys 40 are provided which yieldably rest against the belts.

The abutment or stop 18 can be adjusted 50 both vertically and horizontally and as

shown, is mounted upon brackets 41 which are secured to the standards 6 and can be adjusted vertically and horizontally to a limited extent. In the present instance the brackets have holes of greater diameter than 55 that of the bolts extending therethrough and securing the brackets to the standards.

From the above description it will be readily seen that the drill or the like is straightened between a pair of rollers which revolve 60 in the opposite direction and at the same speed and automatically tend to keep the drill or the like therebetween especially since the rollers are also in vertical alignment. Also means is provided for automatically 65 moving one roller toward and away from the other roller to permit of ready insertion of the drill or the like. Furthermore, the machine is adjustable to permit the same machine to operate upon drills or the like of 70 different sizes.

What I claim as my invention is:

1. In a straightening machine, the combination with a roller, of a cooperating roller spaced therefrom, said rollers adapted to engage a substantially cylindrical member therebetween with its axis substantially parallel to the axes of the rollers, means for rotating said rollers in the same angular direction, means for simultaneously adjusting 80 the opposite ends of one of said rollers and means for automatically moving the other of said rollers toward the adjustably mounted roller.

2. In a straightening machine, the combination with a pair of cooperating rollers spaced from each other for receiving a substantially cylindrical member therebetween with its axis substantially parallel to the axes of the rollers, of means for rotating said 90 rollers in the same angular direction, adjustable bearing blocks rotatably carrying one of said rollers, means for simultaneously adjusting said bearing blocks, bearing blocks rotatably carrying the other of said rollers 95 and means for actuating said last-mentioned bearing blocks to move the roller carried thereby toward the other roller.

In testimony whereof I affix my signature.
CHARLES P. WINEMAN.
